PHARMACEUTICAL TABLET OR
SIMILAR ARTICLE

William S. Tripp, Allegan, Mich., assignor to
L. Perrigo Company, Allegan, Mich.

Filed May 1, 1970, Ser. No. 22,766

Term of patent 14 years

Int. Cl. D28—01; D1—02
U.S. Cl. D16—3

FIG. 2

FIG. 1

FIG. 3

FIG. 4

FIG. 1 is a front elevation of the pharmaceutical tablet or similar article showing the novel ornamental design. The reverse side of the tablet is the same as the side shown;

FIG. 2 is a top plan view thereof;

FIG. 3 is a side elevation thereof; and

FIG. 4 is a bottom plan view thereof.

I claim:

The ornamental design for a pharmaceutical tablet or similar article, substantially as shown and described.
